Lewis C. Bayles
BY
Herbert G. Olden
ATTORNEY

UNITED STATES PATENT OFFICE.

LEWIS CONDICT BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

VALVE.

1,383,373.

Specification of Letters Patent. Patented July 5, 1921.

Application filed July 6, 1920. Serial No. 394,192.

To all whom it may concern:

Be it known that I, LEWIS C. BAYLES, a citizen of the United States, residing at Easton, in the county of Northampton, State of Pennsylvania, have invented a certain new and useful Improvement in Valves, of which the following is a specification.

This invention relates to valves for compressors, pumps and the like and the primary object of the invention is to construct a valve in such manner that when the valve is raised, there is a minimum of obstructing parts, ridges or walls to interfere with the free flow of air through the valve seat and the valve guard. Another important object of the invention is to provide guiding means or ribs on the guard which are continuous and located over the body portions of the valves so that they do not obstruct the flow. Another object of the invention is to secure a plate valve constructed of one piece of sheet metal in which a continuous guiding flange is formed integral with the body portion of the plate by turning one edge substantially at right angles to the plate.

A further object of the invention is to provide a reversible plate valve construction for fluid pressure cylinders which may be used either as an inlet or as a discharge valve as desired.

Further objects of the invention will hereinafter appear and to all of these ends the invention consists of the combinations of elements, arrangements of parts and features of construction substantially as hereinafter fully described and claimed in this specification and shown in the accompanying drawings in which,

Figure 1 is a transverse sectional view of the valve construction on the line 1—1 of Fig. 3.

Fig. 2 is a perspective view of one of the valves.

Fig. 3 is a partial bottom plan view of the guard on the line 3—3 of Fig. 1 looking in the direction of the arrow, and

Fig. 4 is a transverse sectional view partly broken away of a modification.

Referring to the drawings, and at first more particularly to Figs. 1, 2 and 3, A represents a valve seat of the usual form having annular concentric passage-ways B over which the valves, one of which is shown in detail in Fig. 2, are adapted to seat. A guard C having passage-ways D bears at

its center and at its periphery upon the valve seat as indicated in Fig. 1 and limits the lift of the valves. A suitable bolt E preferably has a head F, resting in a recess in the valve seat, and has a nut H with a reduced portion G resting in a corresponding recess in the valve guard for holding the parts together.

The plate valves, one of which is shown in Fig. 2, are preferably constructed of one piece of sheet metal and comprise a body portion J in the form of a flat ring, having one edge formed substantially at right angles thereto to constitute a continuous guiding flange K integral with the body portion. The guard C as shown is provided with guiding means in the form of continuous concentric ribs L located over the body portions J of the valves and co-operating with the guide flanges K to guide the valves and limit their lift. As indicated in Figure 1 the guide flanges K slide along the guiding ribs L as the valves lift and are returned to their seats.

The guiding ribs L on the guard C are provided with socket portions O to receive suitable springs P which bear on the body portions J of the valves for returning the valves to their seats after they lift.

In Fig. 1 the guiding flanges K of the plate valves are at the inner edges of the body portions J of the valves, but in the modification shown in Fig. 4 this construction is reversed and the guiding flanges K' are on the outer edges of the body portions J of the valves. The guard C' in Fig. 4 is substantially like the guard C in Fig. 1, but constructed to permit the guide flanges K' of the valves to bear upon the outer portions of the guide ribs L' instead of upon the inner portions.

By locating the guide ribs L or L' of the guard over the body portions of the valves, they do not obstruct the flow of fluid and when the valves are raised, there is an absence of any obstructing parts, ridges or walls to interfere with the free flow of the fluid between the valve and the valve seat. Furthermore, the valve plates are accurately aligned and guided in their movements.

In order that the entire valve construction may be reversible so that it may be used either as an inlet or discharge valve, a circular flange Q is provided around the periphery of the valve construction, and this flange

as shown is formed partly by the seat A and partly by the guard C or C'. The flange Q is preferably but not necessarily spaced equidistant from the two faces R and S of the valve construction, by forming recessed or cut away portions T and U in this instance of equal depth. By reason of this construction the valve may be placed with either face toward the cylinder. Provision is also afforded for maintaining the end surfaces of the bolt E substantially flush with that surface of the valve construction which faces toward the cylinder. As shown the head F of the bolt rests in a countersunk portion of the seat and the reduced portion G of the nut H rests in a countersunk portion of the guard so that by inserting the bolt from the opposite direction to that shown in Figs. 1 and 4, the head F will be located in the recess provided for the reduced portion G of the nut H, which produces a practically flush surface in the face S.

I claim:

1. A valve construction comprising a valve seat having an annular port, a valve constructed of one piece of sheet metal and comprising a body portion consisting of a flat ring, adapted to seat over said port and having one edge formed at right angles to the body portion to constitute a guide flange, a guard for the valve, and continuous guiding means on the guard located over the body portion of the valve and coöperating with the said guide flange to guide the valve and limit its lift.
2. A valve construction comprising a valve seat having an annular port, a valve constructed of one piece of sheet metal and comprising a body portion consisting of a flat ring, adapted to seat over said port, and having one edge formed at right angles to the body portion to constitute a guide flange, a guard for the valve, and continuous guiding means on the guard located over the body portion of the valve and coöperating with the said guide flange to guide the valve and limit its lift and springs within the guard exerting pressure on the body portion of the

valve for returning the valve to its seat after it lifts.

3. A valve construction comprising a valve seat having a plurality of concentric annular ports, a plurality of valves each constructed of one piece of sheet metal and comprising body portions consisting of flat rings adapted to seat over said ports and having one edge formed at right angles to the body portions to constitute guide flanges, a guard for the valves and continuous concentric ribs on said guard located over the body portions of the valves and coöperating with the said guide flanges to guide the valves and limit their lift and springs seated in the guard and exerting pressure on the body portions of the valves for returning the valves to their seats after they lift.

4. A valve construction comprising a valve seat having a circular port, an annular valve constructed of one piece of sheet metal and comprising a body portion consisting of a flat ring adapted to seat over said port and having one edge formed at right angles to the body portion to constitute a continuous integral guide flange around said edge and continuous guiding means located over the body portion of the valve and coöperating with said guide flange as the valve lifts.

5. A valve construction comprising a valve seat having a circular port, an annular valve constructed of one piece of sheet metal and comprising a body portion consisting of a flat ring adapted to seat over said port and having one edge turned at right angles to the body portion to constitute a continuous integral guide flange around said edge, a guard for the valve having a continuous concentric rib located over the body portion of the valve for guiding the guide flange on the valve and for limiting the lift of the valve and springs seated in said guard and bearing on the body portion of the valve for returning the valve to its seat after it lifts.

In testimony whereof I have signed this specification.

LEWIS CONDICT BAYLES
